GAME TABLE

John Kearsley Mitchell, Villanova, Pa.

Application May 18, 1933, Serial No. 671,609

9 Claims. (Cl. 311—106)

The present invention relates to game tables. The principal object of the invention is to produce a table, preferably of the folding type, which is so constructed that the cover can readily be changed. This will permit the cover to be supplied by the purchaser matching other furnishings in the room, or washable covers may be used that are changed frequently. Also the covers can be so easily changed that there may be supplied covers with various layouts included on them; for example, the covers can be supplied marked with the layout of a checkerboard or with correct layouts for a game such as backgammon. In addition to being so constructed that the cover is readily replaceable, the table of my invention may be provided with a drawer for game supplies, which will automatically be locked shut when the table is folded up, and may also be provided with a large compartment for holding extra covers or other equipment which is accessible by raising one edge of the hinged top.

I have found that if one wishes to make a table of the type referred to with a readily removable cover, the best results can be obtained if there is supplied a substantially flat central area or playing surface over which the cover is to be spread, and an outside frame which is hinged relative to this central flat surface in such a way that when the outer frame is raised and then lowered, it will take a proper and predetermined position relative to the central surface without special guidance by the operator. With this construction, if a cloth or other covering material is spread over the central surface and then the outer frame is brought down, the outer frame will tend progressively to stretch the cloth over the central surface. However, to insure this stretching action with cloths of various thicknesses, and to insure the cloth being held in stretched position, some method of holding the edge of the cloth is necessary. This may be accomplished by any mechanical means tending to hold the edge of the cloth around the central surface and below and spaced away from it, so that when the frame is brought down the cloth will be deflected around the edges of the central surface and tightened. I have found, however, that a simpler method of holding the edge of the covering cloth is to supply resilient and gripping means that are positioned between the outer edge of the central surface and the inner edge of the hinged frame. Such resilient and gripping means may be included in a single element located on the frame or the resilient means may be located on the edge of the central surface and

the gripping means located on the movable frame. In such case, as the frame is swung down, the cloth will be progressively engaged by the gripping means and tensioned against the resilient means, and thereby will be progressively stretched through the downward movement of the outer frame.

The feature referred to as well as various structural improvements embodied in a table of my invention can readily be understood by reference to the accompanying drawings, in which Fig. 1 is a perspective view of a form of table embodying my invention; Fig. 2 is a plan view with a part broken away; Fig. 3 is a section on line 3—3 of Fig. 2; Fig. 4 is a section on line 4—4 of Fig. 2; Fig. 5 is a section similar to Fig. 4 showing the stretching frame in raised position; Fig. 6 is a detail similar to Fig. 4 but showing the leg in retracted position and with a modified construction, and Fig. 7 is a detail of the hinge employed.

As shown in Fig. 1, this table has a central playing surface 10 surrounded by a frame 12 which may be of wood or any other desired material. Depending below the frame 12 is a relatively deep apron 14, its depth being somewhat greater than the maximum thickness of a leg 16. A drawer 18 is provided in one side.

In the illustrative example here shown (see Fig. 2) the four members making up the apron 14 are connected at the corners in any customary fashion and enclose a square frame 20 which ordinarily will be made of wood. I have found that it is economical to make this frame 20 out of a single piece of plywood with the center cut or stamped out. Extending down below member 20 are four wall members 22 engaging a bottom plate 24. As the bottom plate 24 is slightly smaller than the opening in frame 20, the material cut out of the frame can be used to form such bottom plate. As shown in Fig. 3 wall members 22 are preferably made so that they will slide down into the opening in frame 20 but will not drop through owing to the enlargement at the top.

A central surface member 26 is supported by four frame members 28 which normally rest upon the frame 20. However, the member 26 and frame members 28 are so constructed that they can be lifted up from off the compartment formed by wall members 22 and bottom member 24. It is important that when the central surface member 26 is resting with frame members 28 on frame 20, it shall assume a definite predetermined position. This can be assured by pins as indicated at 30 passing through appropriate openings in

frame 20, but as it is somewhat difficult to position such pins in their holes, I have found it advisable to hinge the central surface member 29 to one of the apron members 14 as indicated in Fig. 4. For this purpose a hinge as shown in Fig. 7 is advantageous. With such hinge the number of pins 30 that need be employed can be greatly reduced, or in some circumstances they may be entirely eliminated.

- 10 The frame 12 is likewise pivoted to one of the same apron members 14, and as it will be desirable to lift frame 12 with central surface 26, these two are hinged coaxially by the use of a hinge such as shown in Fig. 7.
- 15 The frame 12 consists of four members connected at the corners in any usual fashion and is here shown as having its inner face grooved to receive a cushion member 32 made of some material such as rubber which will maintain tension between the inner face of frame 12 and the outer face of the frame members 28. With this construction it is obvious that if the frame 12 is raised, with the central surface member 26 left in lowered position as shown in Fig. 5, and a 20 cover of cloth or other material, as indicated at C, is spread over the central surface member, the rubber strip 32 will first squeeze the cover C at the hinge edge and then as the frame is lowered, the cover will be progressively stretched 25 along lines parallel with the hinge until the front edge of the frame (that is, the edge opposite the hinge end) comes into contact, and this will result in a final tensioning against the hinge edge. As a result, the cover C will be stretched and held 30 smoothly covering the surface 26. As the cover should in no case be below the frame 12 it is advisable that the surface 26 be slightly higher than the frame 12, but it is sufficient if these are at the same height.
- 35 In the case described, the rubber strip 32 serves both as a locking and tensioning member. In Fig. 6 a modification is shown in which the outer face of frame members 28 are padded with resilient material such as felt 36 and frame member 12 is formed with an integral tongue 33. In this case the felt 36 serves as the resilient member and the tongue 33 as the locking or gripping member. The action will be substantially similar to that described.
- 40 Ordinarily the tension of the locking and compression or resilient members will be sufficient to hold frame 12 united with central playing surface 26, so that if frame 12 is raised the central playing surface will also be raised and give ready 45 access to the internal compartment. Of course, any desired form of bolt or lock may be supplied to hold these members in position after they are assembled as indicated.
- 50 The legs 16 are intended to be pivoted as is customary with tables of this general type and they may be held folded or in extended position by any form of mechanism such as the clamp 38 which cooperates with a segment 40. Inasmuch as the compartment formed by the bottom member 24 and wall members 22 is of smaller size 55 than the space defined by the apron members 14, there is space for the legs to fold right up against frame 20.

60 In some cases it may be desirable to provide a drawer in addition to the compartment already described. Such a drawer may, for example, be of a size to hold two packs of cards and score sheet and pencil. In order that the drawer shall not interfere with the folding of the legs, this is constructed as clearly shown in Fig. 5 with a false

front 42 which preferably is of the same finish as the apron member 14 and is provided with some pull device such as the ring 44. A connecting plate 46, preferably of metal, joins the false front 42 with the true front 48. The balance of the drawer is of usual construction and does not need further description. In the example here shown the drawer is shown as supported by the bottom member 24 but it is obvious that any other usual form of support may be supplied. Connected 10 with the under face of plate 46 there may be provided a spring clip 50. As shown in Fig. 6 when the legs 16 are closed, one of these legs will clamp up against the clip 50, coming between false front 42 and true front 48 of the drawer, so that the 15 drawer is held in closed position and cannot accidentally open until the legs are unfolded.

20 A table embodying the features described can be made at reasonable cost and I have found that the cover can be changed very readily and that covers of varying thicknesses can be employed on the same structure, and all will be held smoothly stretched over the playing surface 26.

25 It is understood that the example given is only intended by way of illustration and that the same may be modified in many particulars without departing from the spirit of my invention.

30 What I claim is:

35 1. A table top of the type described comprising a frame-work, a flat central member hinged to said framework, and an outer frame hinged directly to the frame-work and adapted when lowered to fit closely around the central member so as to stretch and hold in place a fabric cover spread over the central member. 35

40 2. A structure as specified in claim 1, in which said central member and said outer frame are hinged about a common axis and will remain substantially in a common plane when both are raised. 40

45 3. A table top of the type described comprising a frame-work, a flat central member hinged to said framework, an outside frame member surrounding said central member and adapted to releasably hold a fabric cover stretched over said central member, said frame member being hinged directly to said frame-work and releasable means for connecting said outside frame and central member whereby said frame member can, at will, be raised alone or caused to lift said central member when it is raised. 50

55 4. A structure as specified in claim 3 which further includes a compartment carried by said frame-work which is covered and substantially enclosed when said central member is in lowered position but which will be exposed when said outside frame and central member are lifted together. 55

60 5. A structure as specified in claim 3, in which said central member and said outside frame are hinged about a common axis and will remain substantially in a common plane when both are raised. 60

65 6. In a table of the type described, the combination of a flat central member hinged to a support and adapted to carry a flexible cover, a rigid frame member hinged to said support and adapted to fit around said central member and resilient means between such members adapted to be secured to at least one of said members and adapted to engage and uniformly stretch said cover during movement of said frame member into position about said central member and to hold said cover stretched over the central mem- 70

ber with the edges of the cover extending down between the members.

7. A structure as specified in claim 6, which further includes gripping means between such 5 members as well as resilient means.

8. A structure as specified in claim 6, in which said resilient means is carried by one of said members and a gripping means is carried by the other of said members.

10 9. A table of the type described comprising a frame-work to which legs are connected, a flat

central member hinged to said framework by an offset hinge, an outside frame member surrounding said central member and movable relative to said central member, said hinge being adapted to hold said frame member spaced away from that portion of said frame-work adjacent to said central member when a cloth is spread over said central member and held stretched by said frame member to provide space for the edges of said cloth.
